(57) **CLAIM**

The ornamental design for an inflating needle, as shown and described.

DESCRIPTION

FIG. 1 illustrates a top, right perspective view of an inflating needle incorporating a new four-sided design;

FIG. 2 illustrates a front elevation view thereof;

FIG. 3 illustrates a rear elevation view thereof;

FIG. 4 illustrates a top plan view thereof;

FIG. 5 illustrates a bottom plan view thereof;

FIG. 6 illustrates a left side elevation view thereof; and,

FIG. 7 illustrates a right side elevation view thereof.

In the drawings, the broken lines depict portions of the inflating needle that form no part of the claimed design.
